US00D906656S

(12) United States Design Patent (10) Patent No.: US D906,656 S
Montross et al. (45) Date of Patent:  Jan. 5, 2021

(54) SHOE

(71) Applicant: Reebok International Limited, London (GB)

(72) Inventors: Matthew Montross, Middleboro, MA (US); Toby Birkinhead, Hertfordshire (GB); Daniel Hobson, Waltham, MA (US); Daniel Buonomo, Waltham, MA (US)

(73) Assignee: Reebok International Limited, London (GB)

() Term: 15 Years

(21) Appl. No.: 29/747,220

(22) Filed: Aug. 20, 2020

Related U.S. Application Data

(63) Continuation of application No. 29/697,364, filed on Jul. 8, 2019, now Pat. No. Des. 893,836, which is a continuation of application No. 29/656,061, filed on Jul. 10, 2018, now Pat. No. Des. 854,305, which is a continuation of application No. 29/569,257, filed on Jun. 24, 2016, now Pat. No. Des. 825,163.

(57) CLAIM

The ornamental design for a shoe, as shown and described.

DESCRIPTION

FIG. 1 is a top perspective view of a shoe showing our new design;

FIG. 2 is a bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines in the figures show portions of the shoe that form no part of the claimed design.

1 Claim, 7 Drawing Sheets
